AERIAL TORPEDO

Filed March 16, 1944

UNITED STATES PATENT OFFICE

2,480,927

AERIAL TORPEDO

Nevil Monroe Hopkins, New York, N. Y.; Raymonde B. Hopkins, executrix of said Nevil Monroe Hopkins, deceased, assignor to Raymonde Briggs Hopkins, New York, N. Y.

Application March 16, 1944, Serial No. 526,782

8 Claims. (Cl. 102—49)

1

This invention pertains to torpedoes and more particularly to those fashioned to be fired at comparatively low muzzle velocities at any angle of departure from a gun, the invention having for its principal object the provision of a mechanism which is simple in construction and more efficient in operation than those heretofore proposed.

It is also an object of this invention to introduce ways and means for varying the friction of transmission between a rotary rifle engaging member and the smooth body of the torpedo member, through the introduction of one or more friction discs, for example.

It is also an object of this invention to produce a missile of minimum over-all length when stored aboard a ship, for example, and a maximum over-all length when in flight in its trajectory.

It is also an important object of the invention to provide an anti-aircraft missile, to be discharged from a gun at a high angle of fire, to attain a great height because of the auxiliary rocket drive and to have a time or super-sensitive fuse, for example.

It is also an object of this invention to produce an aerial torpedo containing a maximum weight of high explosive with a minimum weight of container, therefor, to be fired from a rifled gun with a minimum of shock and twisting strain upon the said container.

It is also an object of this invention to fashion a missile in two easily assembled units, the casing with its war-head, detonator and explosive filler, and the tubular tail member with its rocket fuel, respectively, to facilitate loading in a gun.

It is also an object of this invention to produce a torpedo fashioned to receive a smaller shock of departure and lesser strain of spin on leaving a gun, rendering it better adapted to fuses and firing systems, particularly to the magnetic mechanism design.

With these and certain other objects in view, which will become apparent as the description proceeds, the invention consists in the parts and combinations of parts, principles and methods of cooperation, all as will be more fully described and particularly pointed out in the claims.

Referring to the accompanying drawings, form-

ing a part of this specification, in which like numerals designate like parts in all of the views:

Fig. 1 is an elevational view of one design of an aerial torpedo made in accordance with this invention, with the high explosive chamber foreshortened for lack of drawing room, this illustration representing the torpedo when placed in the barrel of a gun;

Fig. 2 is another view of this torpedo, partly in section, after it has left the barrel of a gun;

Fig. 3 is an elevational view of another design of this aerial torpedo, showing the same as when placed in the barrel of a gun;

Fig. 4 is another view, partly in section of the torpedo illustrated in Fig. 3, showing the same after it has left the barrel of a gun;

Fig. 5 is a cross-sectional view of the rotary member, fashioned to engage the rifling of a gun barrel; and

Fig. 6 is a view of the rear end of Fig. 2.

With particular reference to Fig. 1, the numeral 10 designates the ogive-shaped head member of the comparatively thin walled casing containing a high explosive, TNT for example, not shown in the present illustration, while 11 designates the heavy bottom member, and 12 and 13 indicate a pair of thrust bearing friction discs. The numeral 14 represents a rotatable cylindrical member having external rib-like projections indicated at 15, which are fashioned to engage the rifling of a gun barrel, said member being yieldably mounted (as by a friction fit) upon an elongated sleeve member 16 which is free to revolve about a stout tubular member (not shown in this figure of drawing but indicated at 23 in Fig. 2) rigidly connected as by screw threads at one end thereof to the base or bottom member 11 of the head casing, as clearly indicated in Fig. 4.

A plurality of spirally formed metal air fins such as 17 (in one form of the invention) are assembled in spaced relation to each other and rigidly united through the agency of the spaced metal rings such as 18, said rings having a sliding fit longitudinally of the sleeve 16. A slot-way member 19 at its rearmost end 20 is secured to and positioned by the two foremost rings such as 18 and 18½, said member embracing within its slot a stud 21 projecting from the outer surface of said sleeve, said member positioned within a notch formed in the foremost ring 18. Thus it will be

understood that the tail of the bomb or torpedo, comprising the fins 17, is slideable upon the sleeve 16, or in other words said tail is capable of elongation in flight relative the rest of the torpedo. In another form of the invention, said fins may be rigidly attached to the sleeve 16.

It is important to have friction or yieldable fits for the tubular and cylindrical members of this missile particularly when employing spirally disposed air vanes because, on the discharge of the torpedo from a rifled gun the powder gases will cause momentary revolution of the air vanes in a direction opposite to the direction of rotation imparted to the member 14 by the rifling of the gun barrel, and hence there must be provided a slippage or yield. At 22 there is shown a water impact plunger for initiating the ignition of a time fuse within the torpedo or, in place of this type of delayed action firing device, I may use a magnetic firing device, somewhat analogous to the device of the "magnetic mine," or other suitable device, a "depth charge" diaphragm device for example.

In Fig. 2 are shown the spiral fins or vanes 17 and their securing rings 18, extended rearwardly to elongate the missile, thereby adding to the effectiveness of the air vanes under high velocity. The tubular member 23 is secured at its forward end to the heavy bottom or base 11 of the casing of the torpedo (see Fig. 4) and is confined within the sleeve 16, which sleeve is adapted to rotate around said tube. The numeral 24 represents a combustible filler disposed within said tube 23, a slow burning gun powder, for example, suitable for producing a rocket blast. This combustible substance may be a slow burning nitro-cellulose composition, or this tube may contain (properly compartmented) the component parts of a liquid rocket propelling fuel comprising for example a combustible body such as high octane gasoline as one of the component parts, and nitrogen tetra oxide as the other component part. The numeral 25 designates the customary cone-shaped recess, common to rocket design and construction, and the downwardly projecting arrows indicate the paths of gas escape in the rocket blast. Since this torpedo missile is fashioned to be fired from a rifled gun, the combustible material 24 may be directly ignited by the blast of the gun or preferably through the agency of a fuse passing through a plug member, not shown, at the discharge end of the rocket.

The construction of the missile shown in Fig. 3 follows substantially that heretofore disclosed with reference to Figs. 1 and 2, the practical difference residing in the air vanes. In this modification of the invention the forward end portion of each vane is pinned or loosely riveted as at 26 to provide a hinged connection to the sleeve 16, an edge of one vane being indicated at 27, each vane being sheathed or housed (in whole or in part) between guide plates such as 28. The extreme forward end of each vane 27 is cut away, undercut, or otherwise suitably formed (as indicated by the dotted line 29) to provide a stop means for limiting the outward swing of the pivoted vane.

With particular reference to Fig. 4 it will be seen that more of the internal construction is illustrated in the region of the junction of the sleeve 16 with the head member of the torpedo. The forward end of the tube 23 is shown capped or plugged as at 30, and securely screwed in, screw threads not shown, to the heavy base mem-

ber 11, which operation may be done in the process of loading the gun. In the present illustration the torpedo or rocket is shown as in flight after leaving a gun, because the vane members 27-27 are extended under the urge of centrifugal force due to the rapid revolution imparted frictionally to the elongated sleeve 16 by the cylindrical member 14 through the instrumentality of the rifling of the gun barrel. The rearmost end of said tube 23 may be outwardly flared or provided with an external ring device as indicated at 31 to serve as a means for confining the sleeve 16 longitudinally of the tube. The heretofore employed more or less solid high explosive such as TNT indicated at 32 may, if desired or found necessary for some particular use, be replaced as above stated by component parts of a liquid high explosive contained in suitable compartments of the shell member, the such component parts being brought together and mixed during the flight of the missile, the component parts of this liquid high explosive being benzene and nitrogen tetra oxide, for example. A simple pin plunger indicated at 33 is provided to be driven in not by impact with water but only by impact with a more resistant body, the plating of a ship for example, and this may result in the ignition of a time fuse and detonator, for example.

30 The operation of this missile from a rifled gun is as follows.

The missile is introduced into the breech end of the rifle, and pushed forward in the bore to engage the ribs 15 of the rotatable member 14 with the grooves of the rifling as well understood. The missile is then further pushed forward, and the bags of powder, or other containers containing the slow burning nitro-cellulose propellant, are placed behind the vanes of the missile. The breech of the gun is then closed and the powder is ignited, thereupon compressing the considerable air cushion, between the powder bags and the rotatable cylindrical member 14, prior to the forward drive of the missile in the barrel of the gun, which compression materially reduces the shock and strain of firing upon the comparatively thin walls of the torpedo casing. The rotatable cylindrical member 14, of course, serves primarily as a seal or gas check to prevent undue forward escape of the gases of (powder) combustion within the gun barrel without the desired forward propulsion of the missile, but naturally said member will be given rotation by the rifling of the barrel and, through friction, this rotation will be imparted to the sleeve 16 and the air vanes carried thereby, the thrust bearing friction discs such as 12 and 13, interposed between this rotatable member 14 and the base 11 of the body of the missile, serving to lessen the otherwise relatively great twisting strain upon the light wall of the missile container. Thus there is secured efficient forward propulsion of the missile and at the same time, since all of the grooves of the rifling are filled by the ribs of the rotatable member, there is no great escape past said member of hot powder gases into the space between the rifling of the gun and the body of the missile in quantities sufficient to cause erosion or other damage to the missile.

Furthermore, to secure gradual non-shock rotation of the body of a rocket-blast-propelled missile especially when, as and if liquid fuel components are used and mixed at a jet or jets for

discharge therefrom, a plurality of jet nozzles may be fashioned to produce or assist in the rotation of the missile as well as in its propulsion. In addition, it is pointed out that in relieving the gun rifling of the duty of rapidly rotating the main body of the aerial torpedo, much strain is also removed from the gun itself, thereby allowing the use and projection of a heavier aerial torpedo.

Notwithstanding the fact that this missile has been fashioned to be fired economically from a rifled gun at comparatively low muzzle velocities, this being necessary in order not to put undue strain upon the light walled casing of the torpedo yet, to either make up for a loss in muzzle velocity or for other ballistic reasons, it is possible to incorporate the independent rocket drive.

Therefore, it will be appreciated by ballisticians that the missile according to this invention may have ballistic qualities departing from those of a common shell or projectile. That is to say, while the velocity of the common shell or projectile is constantly decreasing because of air resistance, the present missile may maintain or even increase its muzzle velocity through an appreciable portion of its trajectory.

This missile may be either used in skip ballistics, analogous to skip bombing, by travelling swiftly over the surface of the sea after striking the water or, on the other hand and depending upon its angle of departure, its muzzle velocity and/or a combination with the rocket drive, this missile may strike the water at an angle such as to prevent skip travel, and hence dive. It is interesting to point out in this connection that in diving, after striking the water at a proper angle, the missile turns about and pursues a substantially flat trajectory under water to its target. When I say flat trajectory, I mean, of course, comparatively flat to that of its aerial trajectory. A body falls much slower in water than in air and it is this fact which contributes toward the interesting comparatively flat trajectory to the target. When I say the trajectory may be substantially flat, I am keeping in mind that it may travel in an undulatory manner.

In the ballistics of this missile I may elect through a proper time fuse to only start the rocket action subsequent to the dive of the missile in order to secure a maximum of sub-sea travel.

Thus it will be seen that the ogive-capped light casing of this missile does not attain a sudden spinning motion but gradually acquires a spin about its major axis because of the friction between the spinning member 14 and the tubular sleeve member 16, and this spinning motion may be reduced or increased by varying the number of friction bearing washers.

It is obvious that those skilled in the various arts and sciences involved as herein set forth, may vary the details of design and construction, arrangement of parts, as well as the methods, ways and means of the applicant, which would enable them to produce the foregoing invention without departing from its spirit, and therefore, it is not desired to be limited to the precise disclosure, except as may be required by the claims.

What I claim is:

1. A torpedo fashioned to be discharged from a rifled gun, comprising a closed casing, an explosive filler, and a detonator device therefor, a tail member secured to said casing, a gas check member engageable with the rifling of a gun barrel, a friction clutch operatively connecting the gas check member and the casing through the

instrumentality of the tail member, and an air vane mounted upon said tail member.

2. A torpedo fashioned to be discharged from a rifled gun, comprising a closed casing, an explosive filler, and a detonator device therefor, a tubular member attached to an end of said casing, a sheathing disposed about said tubular member with a friction fit, a gas check member fashioned to engage the rifling of a gun about said sheathing with a friction fit, and a spirally disposed air vane rigidly attached to said sheathing.

3. A torpedo fashioned to be discharged from a rifled gun, comprising a closed casing, an explosive filler, and a detonator device therefor, a tubular member attached to an end of said casing, a sheathing disposed about said tubular member with a friction fit, a gas check member disposed about said sheathing with a friction fit, and fashioned to engage the rifling of a gun, and a spirally disposed air vane rigidly attached to said sheathing, and a rocket fuel disposed within said tubular member.

4. A torpedo fashioned to be discharged from a rifled gun, comprising a closed casing, an explosive filler, and a detonator device therefor, a tubular member attached to an end of said casing, a sheathing disposed about said tubular member with a friction fit, a plurality of air vanes rigidly attached to said sheathing and fashioned to revolve said sheathing in one direction in the blast of the powder gases from a gun, and to revolve said sheathing in the opposite direction from the air pressure in flight, the friction fit of the sheathing transmitting friction drive to said casing.

5. A torpedo fashioned to be discharged from a rifled gun, comprising a closed casing, an explosive filler, and a detonator device therefor, a tubular member fashioned for attachment to an end of said casing, a sheathing disposed about said tubular member in a yieldable manner, a gas check member disposed about said sheathing in a yieldable manner, and a plurality of air vanes rigidly attached to said sheathing, fashioned to revolve said sheathing in one direction in the blast of the powder gases from a gun, and to revolve said sheathing in the opposite direction in the blast of air after leaving the gun.

6. A torpedo fashioned to be discharged from the barrel of a rifled gun, comprising a closed casing, an explosive filler, and a detonator device therefor, a tail member secured to said casing, a tubular sheathing rotatably mounted upon said tail member, and a clutch comprising a cylindrical member mounted upon said sheathing and engageable with the rifling of a gun barrel, said cylindrical member frictionally connected to said sheathing and said casing for imparting rotation thereto during the transit of the torpedo through a gun barrel.

7. A torpedo fashioned to be discharged from the barrel of a rifled gun, comprising a closed casing, an explosive filler, and a detonator device therefor, a tail member secured to said casing, a tubular sheathing rotatably mounted upon said tail member, and clutch mechanism providing friction drives between said sheathing and said casing, said mechanism comprising a cylindrical member frictionally mounted upon said sheathing and engageable with the rifling of a gun barrel, said mechanism further comprising thrust members disposed between and frictionally engaging said cylindrical member and said casing.

8. A torpedo comprising a head portion and a tail portion, a sleeve rotatably mounted upon said

tail portion and provided with an outwardly extending stud, an air vane assembly comprising a frame carrying a plurality of air vanes, and slidably mounted axially of said sleeve to increase the over-all length of the torpedo after its launching, said frame having a longitudinal extension overlying said sleeve and provided with a slot-way coextensive therewith and receiving said stud therein, and a clutch mechanism providing friction drives between said sleeve and said head portion.
